UNITED STATES PATENT OFFICE

2,598,600

CLIP FOR GARMENTS OR THE LIKE

Richard Lorence Rank, St. Louis, Mo.

Application January 24, 1949, Serial No. 72,500

6 Claims. (Cl. 24—250)

1

The present invention relates to a clip for garments or the like, and particularly a clip of the type that is usable for sanitary belts, although it will be understood that it is capable of many uses.

The present invention is designed to be an improvement over the clip shown in prior application Serial No. 523,242, filed February 21, 1944, now Patent No. 2,461,083, dated February 8, 1949.

It is an object of the invention to provide a clip that has a snap type action and that will hold securely in closed position. It is a further object of the invention to provide such a clip made with the minimum number of parts and of inexpensive construction. Other objects will appear from the description to follow:

In the drawings:

Fig. 1 is a front elevation of a clip made in accordance with the present invention;

Fig. 2 is a side elevation thereof;

Fig. 3 is a rear elevation of the clip;

Fig. 4 is a front elevation of the main jaw member of the clip;

Fig. 5 is a rear elevation of the main jaw member of the clip;

Fig. 6 is a section transversely to the main jaw member of the clip, taken on the line 6—6 of Fig. 4;

Fig. 7 is another transverse section, taken on the line 7—7 of Fig. 4;

Fig. 8 is a longitudinal section taken on the line 8—8 of Fig. 1, showing the clip closed;

Fig. 9 is a section similar to Fig. 8, but showing the clip partially released; and

Fig. 10 is a longitudinal section of the clip fully released.

The clip comprises three portions consisting of a front jaw member 12, a back jaw member 13, and a latch member 14. The design is such that each of these members may be made from a stamping or other inexpensive process.

The front jaw member 12 preferably has side flanges 15 and 16, and a top flange 17. These afford proper strength and rigidity to the member, and are designed so that the jaw may be made from a stamping. There is a loop 18 shaped as shown with its ends inserted in holes 19 in the flanges 15 and 16, respectively, so that the loop may be attached to the belt or other member to be attached, and have swiveled engagement with the clip.

The front jaw member 12 is preferably constructed with a longitudinal channel-like portion 20 extending upwardly from its bottom nearly to its top. The connecting portion forming

2

the bottom of this channel is cut away to provide an opening 21 adjacent the top, and is likewise slit back at 22 and 23 to provide an elongated spring-like tongue 24, the end of which projects above the top edge of the remainder of the connecting portion of the channel 20, into the opening 21. This tongue 24 is normally sprung or bent backwards a little, as shown in the drawings.

The ends of the wire loop 18 project inwardly of the flanges 15 and 16, and receive the upper hooked-over ends of the back jaw member 13. As shown in Fig. 3, the back member is cut-away downwardly a substantial distance from the top almost to the bottom of the member, so that it is formed with bifurcations 30 and 31 that are bent over in the manner shown in Fig. 8. The extreme ends of these bifurcations are bent preferably about the degree shown in Fig. 8 or a little less, so that, when the back member 13 is swung toward the front about the ends of the loop 18, there will be a slight spring tending to separate the parts 12 and 13.

The latch member 14 is formed of a generally J-shaped strip that is approximately as wide as the channel 20, so that it may be received in that channel, as is indicated in Figs. 1 and 2. Its shorter end is looped around, as shown at 33, and this loop is disposed over two inwardly projecting lugs 34 that are formed as integral parts of the back member 13. They extend out from the edges of the slot forming the bifurcations in this member. Other arrangements may be provided for pivoting the latch member, but this is found most convenient and inexpensive.

From the loop portion 33, the latch member extends upwardly and then over in something of a hairpin or U curve, as indicated at 36. It thence extends downwardly to form the part that projects through the slot 21 of the front member.

The lower edges of the back jaw member 13 are flared outwardly beyond the sides of the front jaw member 12, as shown at 39, for a purpose to appear. The lower portions of the two jaw members are provided with suitable means to engage the material to be clasped, as indicated here by the prongs 40.

Operation

The jaw members 12 and 13 are pivoted at their upper ends. (In the specification and claims, the terms upper and lower are used only for convenience, it being understood that they refer to the parts as they appear in the drawings.) The parts to be clamped are disposed between the engaging portions 40 on the jaw

members. The free end of the latch 14, that passes through the opening 21 of the first jaw member, is in the position of Fig. 10. Squeezing upon the bottoms of this latch member 14 and the second jaw member 13 forces the two jaw members together as illustrated by Figs. 10, 9 and 8. The closing occurs with a snap action.

To open the clip, the flared out parts 39 on the second jaw member 13 are held between the thumb and forefinger of one hand. The forefinger of the other hand draws outwardly on the projecting bottom edge of the latch member 14, which opens up, reversing the closing action. The tongue 24 is preferably disposed to spring backwardly toward a normal position indicated in Fig. 10, to aid in opening of the jaw members.

It will be seen that the top of the tongue 24, and the top edge of the opening 21, are at least as high as, and preferably slightly above, the pivot center at 34. This means that a slight opening up of the U-shaped bend 34 of the latch member occurs when the latch is opened or closed, producing some snap-action effect.

The principal snap action here is provided by the tongue 24. In the position of Fig. 9, the U-shaped bend has engaged the top of the tongue, and the closing of the jaw members has largely displaced the tongue 24 back to the plane of the first jaw member 12. The hinge loop 33 of the latch member 14, which has the additional function of being an abutment means, then engages the tongue 24 somewhat below its free end. Further closing movement of the latch 14, because of the shape of the bend 36, bends this free end of the tongue around the abutment means 33, resisting such closing movement until approximately when the jaw members are fully closed. In the fully closed position of latch and jaw members, the U-shaped bend of the latch has nearer conformation to the shape of the tongue, and therefore relieves the deformation thereof to at least a large extent that assures the snap action. Opening of the latch requires repetition of this bending action.

Prior application Serial No. 523,242 contained many of the desired features of the present clip, but, without the tongue arrangement, it did not afford as good a snap action, nor as secure a holding of the clip in closed position.

It will be understood that variations of the preferred form of the invention may be made, and that the claims are intended to cover such.

What is claimed is:

1. In a clip, first and second jaw members pivoted together adjacent their upper ends, and having engaging portions adjacent their lower ends, an opening through the first jaw member above its engaging portion, a spring-leaf disposed longitudinally of the first member, attached at one end thereto, and with its free end extending adjacent to one edge of the opening, a latch member pivoted to the second jaw member for rocking about an axis that is inward from the free end of the spring-leaf on the first jaw member, the latch member extending in a U-type bend from its axis, in a first direction, then around and into the opposite direction, to provide the U-shaped portion to pass over the end of the spring-leaf, and through the opening, abutment means on the second jaw member projecting toward the first jaw member and against which the spring-leaf engages inwardly from its free end, in closing movement of the latch member and jaw members, the bend in the latch member being shaped to engage the end of the spring-leaf be-

yond the abutment means during such closing movement to deform said end over the abutment means, and to relieve said deformation when the jaw and latch members are in closed positions.

2. In a clip, first and second jaw members pivoted together adjacent their upper ends, and having engaging portions adjacent their lower ends, an opening through the first jaw member above its engaging portion, a spring-leaf disposed longitudinally of the first member, attached at one end thereto, and with its free end extending adjacent to one edge of the opening, a latch member pivoted to the second jaw member for rocking about an axis that is inward from the free end of the spring-leaf on the first jaw member, the latch member extending in a U-type bend from its axis, in a first direction, then around and into the opposite direction, to provide the U-shaped portion to pass over the end of the spring-leaf, and through the opening, abutment means on the second jaw member projecting toward the first jaw member and against which the spring-leaf engages inwardly from its free end, in closing movement of the latch member and jaw members, the bend in the latch member being shaped to engage the end of the spring-leaf beyond the abutment means during such closing movement to deform said end over the abutment means, and to relieve said deformation when the jaw and latch members are in closed positions, the spring-leaf having its attached end on the opposite side of the abutment means and having its initial position extending backwardly from the first jaw member toward the second jaw member, to be engaged by the abutment means during closing movement of the jaw members and apply a force yieldably resisting their closing movement.

3. In a clip, first and second jaw members pivoted together adjacent their upper ends, and having engaging portions adjacent their lower ends, an opening through the first jaw member above its engaging portion, a spring-leaf disposed longitudinally of the first member, attached at one end thereto, and with its free end extending adjacent to one edge of the opening, a latch member pivoted to the second jaw member for rocking about an axis that is inward from the free end of the spring-leaf on the first jaw member, the latch member extending in a U-type bend from its axis, in a first direction, then around and into the opposite direction, to provide the U-shaped portion to pass over the end of the spring-leaf, and through the opening, abutment means on the second jaw member projecting toward the first jaw member and against which the spring-leaf engages inwardly from its free end, in closing movement of the latch member and jaw members, the bend in the latch member being shaped to engage the end of the spring-leaf beyond the abutment means during such closing movement to deform said end over the abutment means, and to relieve said deformation when the jaw and latch members are in closed positions, the latch member being resilient in its bend portion.

4. In a clip, first and second jaw members pivoted together adjacent their upper ends, and having engaging portions adjacent their lower ends, an opening through the first jaw member above its engaging portion, a spring-leaf disposed longitudinally of the first member, attached at one end thereto, and with its free end extending adjacent to one edge of the opening, a latch member pivoted to the second jaw member for rock-

ing about an axis that is inward from the free end of the spring-leaf on the first jaw member, the latch member extending in a U-type bend from its axis, in a first direction, then around and into the opposite direction, to provide the U-shaped portion to pass over the end of the spring-leaf, and through the opening, abutment means on the second jaw member projecting toward the first jaw member and against which the spring-leaf engages inwardly from its free end, in closing movement of the latch member and jaw members, the bend in the latch member being shaped to engage the end of the spring-leaf beyond the abutment means during such closing movement to deform said end over the abutment means, and to relieve said deformation when the jaw and latch members are in closed positions, the latch member having rolled-over ends for pivotal mounting on the second jaw member, said rolled-over ends comprising the abutment means aforesaid.

5. In a clip, first and second jaw members pivoted together adjacent their upper ends, and having engaging portions adjacent their lower ends, an opening through the first jaw member above its engaging portion, a spring-leaf disposed longitudinally of the first member, attached at one end thereto, and with its free end extending adjacent to one edge of the opening, a latch member pivoted to the second jaw member for rocking about an axis that is inward from the free end of the spring-leaf on the first jaw member, the latch member extending in a U-type bend from its axis, in a first direction, then around and into the opposite direction, to provide the U-shaped portion to pass over the end of the spring-leaf, and through the opening, abutment means on the second jaw member projecting toward the first jaw member and against which the spring-leaf engages inwardly from its free end, in closing movement of the latch member and jaw members, the bend in the latch member being shaped to engage the end of the spring-leaf beyond the abutment means during such closing movement to deform said end over the abutment means, and to relieve said deformation when the jaw and latch members are in closed positions, the opening in the first member having

an edge engageable by the latch member, the spring leaf extending a short distance beyond said edge.

6. A clip comprising first and second jaw members pivoted together at their upper ends and having engaging portions at their lower ends, an opening near the top of the first member having a lower edge, slits extending from said lower edge downwardly to provide a spring-like tongue joined at its base to the first member below the opening, the upper end of the tongue projecting a short distance above the lower edge of the opening; a latch member of resilient material having one end pivoted to the second jaw member downwardly from the lower edge of the aforesaid opening, said latch member extending upwardly, forwardly, and downwardly from its pivot in a U-type bend, with its free end extending through the opening in the first jaw member, the pivoted end of the jaw member providing abutment means extending toward the first jaw member, and engageable with the spring-like tongue below its end, the bend of the latch member being engageable with the free end of the tongue during latching and closing of the jaw members, to deform the said end over the abutment means, said bend being shaped to relieve the deformation when the jaw members are fully closed and the free end of the latch member is swung toward the first jaw member to its latching position.
